UNITED STATES PATENT OFFICE

115,462

DESIGN FOR A BOX OR SIMILAR ARTICLE

Wah Chan Thom, Honolulu, Territory of Hawaii

Application February 24, 1939, Serial No. 83,191

Term of patent 7 years

To all whom it may concern:

Be it known that I, Wah Chan Thom, a citizen of the United States, residing in the city of Honolulu, in the county of Honolulu, in the Territory of Hawaii, have invented a new, original, and ornamental Design for Boxes or Similar Articles, of which the following is a specification, reference being had to the accompanying drawings, forming a part thereof.

In the drawings:

Fig. 1 is a perspective view, on a slightly smaller scale, of a box or similar article showing my new design.

Fig. 2 is a top plan view thereof.

Fig. 3 is a front elevation thereof.

Fig. 4 is an end elevation thereof.

The ornamental features displayed upon the end panel illustrated in Figs. 1 and 4 are duplicated upon the opposite end panel, and the ornamental features displayed upon the front panel illustrated in Figs. 1 and 3 are duplicated upon the rear panel.

I claim:

The ornamental design for a box or similar article, as shown and described.

WAH CHAN THOM.
